UNITED STATES PATENT OFFICE

ANTONY SCOTT STOKES, OF IPSWICH, ENGLAND

TRAVELING CRANE

Application filed September 26, 1929, Serial No. 395,439, and in Great Britain October 4, 1928.

This invention relates to traveling cranes of the kind in which the crane truck, when traveling, is relieved of part of the weight of the crane by means of one or more auxiliary or relieving bogies placed at the front and rear of the crane truck or at one end only and each detachably connected thereto by a relieving girder; jacks or the like being provided in order to enable the desired proportion of the weight of the crane to be transferred to the bogie or bogies.

In cranes of this type as hitherto built each relieving girder has been so connected to the bogie that, whilst the latter was capable of swivelling slightly about a vertical axis it could not move about a horizontal axis. Consequently, when the bogie entered a portion of the track in which there was a difference in the levels of the rails, for example when entering a curve, one side of the bogie was more heavily loaded than the other, so that there was a tendency to derail the bogie. Moreover, should the crane, on reaching the place at which it was required for use, stop at a point where the rail levels were different, the heavier load on one side of the bogie threw a side load on the pin connecting the relieving girder to the crane truck so that the withdrawal and subsequent insertion of this pin was difficult. The present invention has for its object to obviate these disadvantages.

According to the present invention in a crane of the kind described the connection between the relieving girder and the bogie is such that in addition to a swivelling movement about a vertical axis the bogie is permitted to oscillate about an axis or axes in the horizontal plane so as to allow the bogie to roll, that is to say rock transversely, or pitch, that is to say rock in the fore and aft direction, or to perform both these movements simultaneously.

To this end the relieving girder may be connected to the bogie by means of a ball joint associated with the vertical pin about which the bogie can swivel. Alternatively, the girder may terminate in a pin projecting longitudinally in the fore and aft direction and passing freely through a yoke which in

turn is mounted on the bogie frame so as to allow the latter to rock about a transverse axis, the whole being combined with a vertical pin to permit the bogie to swivel, means being provided also for raising and lowering the girder relatively to the bogie in order to adjust the proportion of the weight of the crane taken by the bogie.

The relieving girder is conveniently connected to the crane truck by means of a removable pin passing through lugs on the girder and on the crane truck and, in order to facilitate the insertion of the pin, guides may be provided on the lugs so formed that, operating in conjunction with the relative movement permitted to the bogie and girder by reason of the connection between them, the holes for the coupling pin can be brought readily into register. Similarly the guides or lug formations tend to prevent binding of the lugs on the pin and allow the latter to be withdrawn easily.

One form of crane according to the invention will now be described by way of example with reference to the accompanying drawings, in which

Figure 1 shows the crane somewhat diagrammatically in side elevation,

Figure 2 is a side elevation partly in section on an enlarged scale of one of the auxiliary bogies, and

Figure 3 is a plan of the auxiliary bogie shown in Figure 2.

Referring to Figure 1, the crane proper, including its controlling mechanism, as it forms no part of the present invention is shown in broken lines and is mounted on a rotatable table A¹ of a main truck A to each end of which are connected, for purposes of traveling, in train and at other times bogies B, B¹.

Referring now to Figures 2 and 3, each bogie comprises a frame C which supports a relieving girder D by means of which the truck A is attached to the bogie B and part of the weight of the truck is transferred to the bogie in a manner hereinafter to be described. The girder D is deeper at one end D¹ than at the other end D² so that it is substantially triangular in elevation (Figure 190

2) and the end D² is permanently secured to the frame C by means of a ball connection. This connection comprises two cup-shaped members E, E¹ mounted opposite one another on the end D² of the girder D and a ball member F adapted to turn within the cup-shaped members E, E¹ which thus serve as a bearing for it. The ball member F is bored to receive a vertical spindle G the upper end of which passes through a bearing H on the top of the bogie frame C and is screwthreaded at G¹ to receive a nut J the lower end of the spindle G being held in a guide bearing H¹ carried at the bottom of the frame C. Forming part of or fixed to the spindle G and immediately below the ball member F is a shoulder G² on which the ball member rests so that the spindle supports the end D² of the relieving girder D. On the nut J is a worm wheel J¹ which cooperates with a worm J² keyed or otherwise fixed to a shaft K mounted in bearings L and L¹ on top of the frame C, the shaft K having squared ends K¹, K² for a handle by means of which the shaft K can be turned to rotate through the worm gear J¹, J² the nut J and thus raise or lower the end D² of the girder D relative to the bogie frame C.

To the upper and lower edges of the free end D¹ of the girder lugs M and M¹ are attached for connecting the girder to the frame of the crane truck A. Two pairs of lugs N and N¹ are provided on the truck A and are arranged one above the other so that the lugs M and M¹ on the girder D can enter the space between the two lugs N and the two lugs N¹ respectively. The forward end or nose of each of the lugs M and M¹ is made circular and concentric with a hole for a connecting pin whilst the inner end or back of the space between the two lugs of each pair N and N¹ is also made concentric with the pin holes in these lugs and of the same radius as the nose of the girder lug M or M¹ as the case may be as clearly shown in Figure 3. The sides of the space between the lugs are closed in and their inner surfaces diverge towards the mouth of the space as shown in dotted lines at O and O¹ in Figure 3 so as to act as guides for the lugs M and M¹.

Thus when the lugs M and M¹ enter their respective spaces their forward ends bear against and exactly fit the inner end of the spaces between the pair of lugs N and N¹ respectively so that the holes in the lugs M, M¹ register automatically with those in the lugs N and N¹ and a connecting pin can readily be inserted. The connecting pin P is formed with two enlarged portions P¹ and P² arranged to fit in the holes in the lugs M, N and M¹, N¹ respectively the part of the pin connecting the two portions P¹ and P² being of reduced diameter. This construction of pin facilitates the insertion and withdrawal of the pin and reduces any tendency to bind-

ing which might occur were the pin of the same diameter throughout.

In order to prevent the pin P being shaken loose during movement of the crane and bogies a locking lever Q is provided which fits into a recess P³ in the pin P and in suitable lugs or supports on the upper of the two lugs N. The end D¹ of the relieving girder D is supported on the frame C by a compression spring R to which it is connected by a rod S so that when the bogie is disconnected from the truck the weight of the girder is taken by the spring R and the ball and socket bearing F. If desired, means such, for example, as laterally projecting handles (not shown) may be provided at the free end D¹ of the girder D to facilitate guiding it into position when connecting the truck and the bogie.

The girder D becomes operative to transfer some of the weight of the crane from the truck A to the bogie B by tightening the nut J and thus lifting the end D² of the girder in a manner previously described.

It will be appreciated however that the "universal" nature of the connection between the frame C and the girder end D² relieves the connecting pin P at the other end D¹ of the girder of all lateral load so that, when the crane is stationary and all its weight has been transferred back to the truck A by slackening the nut J, the pin P can be readily withdrawn without loss of time.

Instead of employing a ball connection between the relieving girder and the bogie any other form of connection which will give the bogie the desired freedom of movement may be used. For example, the girder may terminate in a longitudinally projecting pin passing freely through a yoke mounted in bearings transversely of the bogie frame, these bearings being provided with means for raising and lowering them in order to permit adjustment of the proportion of the weight of the crane which is taken by the bogies and the whole combined with a swiveling or pivot device.

It will further be understood that the above arrangements have been described by way of example only and that the details of construction may be varied without departing from the scope of the invention as set forth in the appended claims.

What I claim as my invention and desire to secure by Letters Patent is:—

1. In a traveling crane, the combination of a crane truck, a relieving bogie for carrying part of the weight of the crane when traveling, a relieving girder for transferring weight from the truck to the bogie, means for connecting one end of the girder to the truck, and a connection between the other end of the girder and the bogie such that the bogie is permitted to swivel about a vertical axis and also to oscillate about axes in the hori-

zontal plane so as to allow the bogie to roll and to pitch.

2. In a traveling crane, the combination of a crane truck, a relieving bogie for carrying part of the weight of the crane when traveling, a relieving girder for transferring weight from the truck to the bogie, a removable pin for connecting one end of the relieving girder to the truck, and a connection between the other end of the girder and the bogie such that the bogie is permitted to swivel about a vertical axis and also to oscillate about axes in the horizontal plane so as to allow the bogie to roll and to pitch.

3. In a traveling crane, the combination of a crane truck, a relieving bogie for carrying part of the weight of the crane when traveling, a relieving girder for transferring weight from the truck to the bogie, means for connecting one end of the girder to the truck, a connection between the other end of the girder and the bogie such that the bogie is permitted to swivel about a vertical axis and also to oscillate about axes in the horizontal plane so as to allow the bogie to roll and to pitch, and means for raising and lowering the end of the relieving girder connected to the bogie in order to adjust the proportion of the weight of the crane taken by the bogie.

4. In a traveling crane, the combination of a crane truck, a relieving bogie for carrying part of the weight of the crane when traveling, a relieving girder for transferring weight from the truck to the bogie, means for connecting one end of the girder to the truck, a ball joint between the other end of the girder and the bogie such that the bogie is permitted to swivel about a vertical axis and also to oscillate about axes in the horizontal plane so as to allow the bogie to roll and to pitch, and means for raising and lowering the ball joint in order to adjust the proportion of the weight of the crane taken by the bogie.

5. In a traveling crane, the combination of a crane truck, a relieving bogie for carrying part of the weight of the crane when traveling, a relieving girder for transferring weight from the truck to the bogie, means for connecting one end of the girder to the truck, a ball socket on the other end of the girder, a vertical spindle supported on the bogie and about which the bogie can swivel, a ball carried by the spindle which cooperates with the socket on the girder, and means associated with the spindle for raising and lowering the ball relatively to the bogie so as to adjust the proportion of the weight of the crane taken by the bogie.

6. In a travelling crane, the combination of a crane truck, a relieving bogie for carrying part of the weight of the crane when traveling, a relieving girder for transferring weight from the truck to the bogie, lugs mounted on the end of the truck and having pin holes

therein, cooperating lugs on one end of the girder and having corresponding pin holes therein, guides associated with the lugs on the truck to ensure that the pin holes in the lugs automatically register when the lugs on the girder enter into engagement with those on the truck, a removable pin passing through the holes in the cooperating lugs, a connection between the other end of the girder and the bogie such that the bogie is permitted to swivel about a vertical axis and also to oscillate about axes in the horizontal plane so as to allow the bogie to roll and to pitch, and means for raising and lowering the end of the relieving girder connected to the bogie in order to adjust the proportion of the weight of the crane taken by the bogie.

7. In a traveling crane, the combination of a crane truck, a relieving bogie for carrying part of the weight of the crane when traveling, a relieving girder for transferring weight from the truck to the bogie, lugs mounted on the end of the truck and having pin holes therein, cooperating lugs on one end of the girder and having corresponding pin holes therein, guides associated with the lugs on the truck to ensure that the pin holes in the lugs automatically register when the lugs on the girder enter into engagement with those on the truck, a removable pin passing through the holes in the cooperating lugs, a ball socket on the other end of the girder, a vertical spindle supported on the bogie and about which the bogie can swivel, a ball carried by the spindle which cooperates with the socket on the girder, and means associated with the spindle for raising and lowering the ball relatively to the bogie so as to adjust the proportion of the weight of the crane taken by the bogie.

In testimony whereof I have signed my name to this specification.

ANTONY SCOTT STOKES.
